UNITED STATES PATENT OFFICE

SAUL WILLIAM FRUCHTMAN, OF BROOKLYN, NEW YORK, ASSIGNOR TO EVERLITE NOVELTY MFG. CORP., A CORPORATION OF NEW YORK

DESIGN FOR A LAMP BASE OR ARTICLE OF ANALOGOUS NATURE

Application filed June 27, 1930. Serial No. 36,209. Term of patent 3½ years.

To all whom it may concern:

Be it known that I, SAUL WILLIAM FRUCHTMAN, a citizen of the United States, and a resident of Brooklyn, county of Kings, and State of New York, have invented a new, original, and ornamental Design for Lamp Bases or Articles of Analogous Nature, of which the following is a specification, reference being had to the drawing forming a part thereof.

lamp base or article of analogous nature taken from the front or rear; and

Figure 2 is a diagrammatic end view of the pedestal portion of the lamp base or article of analogous nature shown in Figure 1, the horse and rider being omitted.

I claim:

The ornamental design for a lamp base or article of analogous nature substantially as shown and described.

SAUL W. FRUCHTMAN.
